UNITED STATES PATENT OFFICE

EDWIN M. WYATT, OF MADISON, WISCONSIN, ASSIGNOR, BY MESNE ASSIGNMENTS, TO
AMERICAN FACE BRICK RESEARCH CORPORATION, A CORPORATION OF ILLINOIS

PATTERNEDE BRICK WALL

Application filed February 20, 1929. Serial No. 341,351.

This invention relates to improvements in patterned brick wall, of which the following is a specification:

The present invention is directed to a brick wall in which the bricks, of standard dimensions, are so arranged as to display patterned groups which include, in each group, a plurality of bricks variously arranged to display different faces of the respective bricks in the constituents of a pattern which repeats itself throughout the wall, thereby introducing into the wall structure a pleasing variation in appearance, and at the same time, by reason of the repetition of the pattern group, preserving a desirable uniformity in the structure of the wall. Furthermore, the grouping of the bricks in pattern groups of the character presently to be described subserves the purpose of tying together or integrating the various portions of the wall structure in such a way as to provide for a substantial saving in the use of material, and to secure structural advantages due to the use of header bricks in the group arrangement.

The grouping principle exemplified in the present invention is susceptible of various modifications, which, however, are in the main elaborations of the simpler arrangement, and are provided by including what may be termed supplemental elements in the pattern group.

In certain of the group arrangements presently to be described, the grouping constituents comprise bricks standing on edge as bull stretchers, and bricks presenting their ends to the wall face, termed "header bricks". In the more elaborate exemplifications of the group pattern, bricks are included which are laid flatwise as stretcher bricks, and by the inclusion of bricks set in these three different arrangements, the pattern group whether in simple form or more elaborate form is built up. In order to accentuate the horizontal lines in the brick courses, all of the bricks are laid with their major dimensions extending horizontally, and horizontal courses are preserved in the wall structure although the courses are of greater vertical width and are provided by a grouping of

bricks rather than by laying single bricks in horizontal courses in conformity with the standard practice.

In the drawings illustrating the invention, Figure 1 is an isometric view of a brick wall exemplifying the simplified pattern arrangement of the present invention.

Figure 2 is a similar view showing the corner of a wall embodying a pattern which introduces a sub-group in conjunction with the group units of Figure 1.

Figures 3 and 4 are detail views showing the constituent arrangement of the bricks in the groups.

Figure 5 is an isometric view showing a variant of the wall in Fig. 2 and including intermediate bricks provided as fillers within the center of the wall.

Figure 6 is an isometric view of a wall which constitutes a variant of the wall of Figure 2 by introducing an additional sub-group unit.

And Figure 7 is a detail view showing the sub-group unit additionally introduced into the wall of Figure 6.

Referring to Figure 1, the group unit which, for convenience, we may term the main group unit, constitutes a brick 10 standing on edge or in bull-stretcher arrangement to present its broad side to the face of the wall together with two superposed header bricks 11 resting upon the edge of the bull stretcher brick 10. A similar arrangement is observed in the building of the rear wall face which leaves a gap which is bridged over by the header bricks which thus serve to bond together and integrate the front and rear portions of the wall structure. A single pattern course will comprise units with the constituent headers above the bull stretchers alternating with units in which the headers lie below the bull stretchers, which arrangement serves to tie the wall together at all levels, thereby providing a partially hollow wall which, however, possesses practically the same elements of strength and ruggedness as a wall in which the spaces between the front and rear courses are completely filled up. It will be observed that a definite horizontal pattern course is preserved throughout the

wall since the mortar lines are continuous between the group courses made up as above described although, within a single group course, the pattern arrangement provided by 5 the alternately reversed arrangement of the constituents of the pattern unit introduces a pleasing design which serves to break the monotony in the appearance of the wall.

In the wall of Fig. 2, the pattern group 10 includes the main unit previously described, which is alternated by a secondary unit or sub-group consisting of a bull-stretcher brick 12, superposed upon a stretcher brick 13. This 15 sub-group is clearly shown in Fig. 4. In this wall arrangement, the header bricks of the main group units as shown, all lie above the bull stretcher brick within the same brick unit and the arrangement, of necessity, separates the tie bricks to a greater extent than is the 20 case in the wall of Fig. 1. However, if it is desired to additionally reinforce the wall across the planes occupied by the stretcher bricks 13, this can readily be done by the inclusion of intermediate bull stretchers 14, 25 as in Fig. 5, which rest upon the inwardly projecting edges and bridge the slight gap between them, and the provision of these intermediate bonding bull stretcher bricks results in the construction of a practically solid 30 wall built in group courses and completely tied together or integrated at all points.

A still further variation is shown in Fig. 6, which, in addition to the main group unit of Fig. 1, and the first sub-group of Fig. 4, 35 includes the second sub-group shown in Fig. 7, which comprises a header brick 15 standing upon and bridging the space between a pair of half bricks or brick bats 16. As shown in Fig. 6, in certain of the second sub-group 40 units the header brick 15 is arranged above the half bricks 16 and in other cases the relation is reversed with due regard for the desirability of breaking joints with the constituents of the immediately adjacent groups 45 which may be either the main group first described or the first sub-group comprising a bull stretcher standing upon a stretcher. As shown in Fig. 6, the second sub-group may be variously employed in building the wall 50 and its use introduces a pleasing variation where it is desired to break the regularity of the wall structure by the introduction of a smaller sub-group unit than either of the other units. In this case, as in the others, 55 although the wall pattern is elaborated by the introduction of an additional sub-group unit, it will be observed that the same general horizontal pattern course arrangement is retained, the mortar lines being continuous 60 between the pattern courses, howsoever the constituent elements of the courses may be arranged.

The present invention is one which so utilizes ordinary bricks of standard dimensions as to introduce into the completed wall

certain elements of recurrent design which clearly distinguish the appearance of the wall from that commonly presented by brick walls and at the same time, in each instance, the arrangement sub-serves a definite purpose 70 in knitting together and integrating the structure of the wall as a whole.

In the present invention, furthermore, the header bricks are so distributed throughout the wall structure as to provide a header brick 75 for each 30 to 60 square inches of wall surface, which affords a much more intimate bond between the front and rear wall sections than is ordinarily required by building codes, and at the same time the header bricks and vertical joints in the wall structure are distributed much more advantageously than is customary in brick walls of standard construction. In particular, the vertical joints 80 in the present wall do not come one above the other, and consequently the centers of stretcher bricks do not come directly over the centers of succeeding bricks, so that the strains are carried diagonally into the wall, resulting in a much stronger structure than 85 that afforded by brick walls constructed in the conventional manner.

Although the invention has been described with considerable particularity, it is not the intention to limit the pattern arrangement 90 strictly to that shown and described since variants thereof within the scope of the appended claims may be introduced without departing from the spirit of the invention.

I claim:

1. A brick wall consisting of superposed pattern courses, the contiguous pattern courses being separated by uninterrupted horizontal mortar lines, each pattern course including pattern units comprising a brick standing on edge as a bull stretcher and a brick laid flatwise, the superposed relation of the bull stretcher brick and the flat lying brick of each unit alternating in the pattern units in the same course to break joints between pattern units, and the pattern units in contiguous courses breaking joints to present the vertical joints between the pattern units in staggered relation in alternate courses.

2. A brick wall consisting of superposed pattern courses, the contiguous pattern courses being separated by uninterrupted horizontal mortar lines, each pattern course including pattern units comprising a brick standing on edge as a bull stretcher and a brick laid flatwise, the superposed relation of the bull stretcher brick and the flat lying brick of each unit alternating in the pattern units in the same course to break joints between pattern units, and the pattern units in contiguous courses breaking joints by an overlap of approximately one-fourth of the length of the pattern units to present the vertical joints between the pattern units in staggered relation in alternate courses.

3. A brick wall consisting of superposed pattern courses, the contiguous pattern courses being separated by uninterrupted horizontal mortar lines, each pattern course including pattern units each comprising a brick standing on edge as a bull stretcher, and two header bricks bonded flatwise across the edge thereof and presenting their ends in flush relation to the exposed surface of the wall structure, the superposed relation of the bull stretcher brick and the flat lying bricks of each unit alternating in the pattern units in the same course to break joints between pattern units, and the pattern units in contiguous courses breaking joints to present the vertical joints between pattern units in staggered relation in alternate courses. 70
4. A brick wall consisting of superposed pattern courses, the contiguous pattern courses being separated by uninterrupted horizontal mortar lines, each pattern course including pattern units comprising a brick standing on edge as a bull stretcher, and two header bricks bonded flatwise across the edge thereof and presenting their ends in flush relation to the exposed surface of the bull stretcher, the superposed relation of the bull stretcher and the flat lying header bricks alternating in the pattern units of the same course, and the pattern units in contiguous courses breaking joints by an overlap of approximately one-fourth of the length of the pattern units to present the vertical joints between the pattern units in staggered relation in alternate courses. 75
5. A brick wall comprising a front tier consisting of superposed pattern courses, the contiguous pattern courses being separated by uninterrupted horizontal mortar lines, each pattern course including pattern units comprising a brick standing on edge as a bull stretcher and a brick laid flatwise, and two header bricks bonded flatwise across the edge thereof and presenting their ends in flush relation to the exposed surface of the bull stretcher, the superposed relation of the bull stretcher and the flat lying header bricks alternating in the pattern units of the same course, and the pattern units in contiguous courses breaking joints to present the vertical joints between the pattern units in staggered relation in alternate courses. 80
6. A brick wall comprising a front tier consisting of superposed pattern courses, the contiguous pattern courses being separated by uninterrupted horizontal mortar lines, each pattern course including pattern units comprising a brick standing on edge as a bull stretcher, and two header bricks bonded flatwise across the edges thereof and presenting their ends in flush relation to the exposed surface of the bull stretcher, the superposed relation of the bull stretcher and the flat lying header bricks alternating in the pattern units of the same course, and the pattern units in contiguous courses breaking joints by an overlap of approximately one-fourth of the length of the pattern units to present the vertical joints between the pattern units in staggered relation in alternate courses. 85
- In witness that I claim the foregoing I have hereunto subscribed my name this 13th day of February, 1929.
